U. S.

J. Benjamin Hinckley of Frye'sville, Maine
Letters Patent.

The Schedule referred to in these Letters Patent and making part of the same containing a description in the words of the said Benjamin Hinckley himself of his improvement in the mode of diminishing friction on the bearings of shafts, axles, &c. & other machinery.

To all to whom these presents shall come, to wit, known that J. Benjamin Hinckley of Frye'sville in the County of Kennebec and State of Maine, Machinist, have invented a new and useful improvement in the mode of diminishing friction on the bearings of axles, shafts, yokes, and other machinery, and that the following is a full and exact description of the construction and operation of the said machinery as invented and improved by me. Fig. 1. of the six-faced drawings, which constitute a part of this description, represents a front view of the box and rollers without the shaft being inserted. A represents the outside of the box. B represents the outside of the plate making a part of the box, & A.A.A. represents four small anti-friction rollers running in the box. Fig. 2. represents the whole of the box with the shaft inserted. B is the plate. A. The outside of the box. Fig. 3. represents the inside of the plate B. of Fig. 3. the rim of the plate and of the part of the surface within the projection forming the groove in the box. Fig. 4. represents the bars & rollers as they are when in the box. C.C. are the bands intended to keep the rollers in their places, formed with oblong holes in which the part of the rollers play. a.a.a. represent the rollers. These four last described figures of the drawings constitute what I call the anti-friction box and may be formed of cast iron or any other suitable metal. Fig. 5. represents the shaft or axle-tree with two centre wheels and two anti-friction rollers playing between the wheels. E represents this shaft. D.D. are centre wheels upon the shaft. F a small section of the framework of a carriage, or other framework. b.b. are two anti-friction rollers playing between the two centre wheels in such a manner as to prevent side friction of the rollers inside of the box. G represents the end of the shaft which comes through the hub of the a. wheel when used on Carriages. C.C. show the projection on each side of the groove in the shaft in which the rollers in the box are intended to run and this groove will be the bearing of the shaft. Fig. 6. represents a view of the

two centre wheels ~~and~~ ^{which} are intended with the anti-friction rollers between them. The two centre wheels with the anti-friction rollers are intended to take off the side friction, and the box rollers are intended to take off the friction of the bearings. These can be applied to carriages, Mills, Steamboats, or in any other machinery where a shaft is used. I do not pretend to do away with all friction upon a shaft, but the arrangement of the rollers taking the bearing on the outer edges of the rollers will materially diminish the friction. Having described my said improvement, and the manner ⁱⁿ which it is intended to operate, I do hereby declare that what I claim as new and for which I ask the exclusive use consists in the mode herein before described of applying anti-friction rollers to the cylindrical shaft or other parts of machinery and the Box bearing before described. The attaching this Box to a carriage body or frame works, the groove in this shaft, or axlebox and in this box to keep the rollers and ^{the} shaft in their respective places so as to prevent their interferences with each other's motion. The two centre wheels upon the shaft with the anti-friction rollers between them as herein before described to diminish side friction and the arrangement of the several parts of the machinery as herein before described.

Testd.
